ATTORNEY.

UNITED STATES PATENT OFFICE.

HAROLD G. MARTIN, OF PHILADELPHIA, PENNSYLVANIA, ASSIGNOR OF ONE-HALF
TO MICHAEL H. NEWGIRG, OF BALTIMORE, MARYLAND.

BEARING-BRASS.

1,383,958.

Specification of Letters Patent. Patented July 5, 1921.

Application filed November 23, 1920. Serial No. 426,012.

To all whom it may concern:

Be it known that I, HAROLD G. MARTIN, a citizen of the United States of America, residing at Philadelphia, in the county of Philadelphia, and State of Pennsylvania, have invented certain new and useful Improvements in Bearing-Brasses, of which the following is a specification.

This invention relates to an improvement 10 in bearing brasses, and particularly in those brasses designed for use at the rear end of the main connecting rod of a locomotive. In such uses the ordinary brasses, owing to the continual thrust of the connecting rod in 15 opposite directions, are of comparatively short life, being broken at substantially the center of such brasses as a result of the rod thrust.

The present invention is directed to reinforcing such brasses, particularly with a 20 view to overcoming such liability to breakage, and consists in casting in the brass proper a reinforce section, which is particularly constructed for strength at the desired 25 point, and also with a view of preventing accidental displacement of the reinforce.

In the drawings:

Figure 1 is a view in end elevation of co-operating bearing brasses, the improved reinforce being shown in dotted outline. 30

Fig. 2 is a side elevation of the same.

Fig. 3 is a vertical section through the brass.

Fig. 4 is a diagrammatic view, illustrative 35 of the application of the brass in the locomotive structure.

In the present invention, the brass 1, otherwise of ordinary construction and material, is interiorly provided, preferably in casting, 40 with a reinforce strip of section 2. This reinforce section is of substantially the full width of the brass between the edge flanges, and of somewhat less length circumferentially than that of the brass. The respective 45 ends of the reinforce, which are wholly embedded within the brass material, are formed with hook terminals, as 3, to insure a firm interconnection of the reinforce with the material of the brass, and prevent possibility 50 of displacement.

The reinforce is of substantially uniform and similar curvature from the ends toward the center, as at 4, while the central portion is on a curvature of somewhat greater radius, as at 5, whereby such central portion of the 55 reinforce is of somewhat greater thickness than the end portions.

As previously stated the improved brass is designed particularly for the rear ends of the main connecting rods of locomotives, and 60 that in such use the brasses, owing to the thrust of such rods, are continually broken across the center of such brass, that is between the ends thereof, as indicated by the line 6. The improved reinforce is therefore 65 strengthened at such line of possible breakage, by the thickening described, so that in addition to strengthening the brass as a whole, a particular strain is effectively compensated for. 70

The material of the contemplated reinforce may be that best adapted for the purpose, though all necessary conditions entering into its use with the ordinary brass material should be taken into consideration in 75 the use of any particular material.

If desired, and as preferred the reinforce may be formed with one or more holes 7 through which the metal of the brass will 80 find its way in casting. A secure holding of 80 the reinforce is thus provided, and the proper and accurate position of the reinforce in the brass maintained throughout the life of the same.

Having thus described the invention, what 85 is claimed as new, is:—

A bearing brass having a reinforce section embedded therein, said section having hook-ends and being curved adjacent the ends in conformity with the curvature of the 90 brass, the intermediate portion of the reinforce being thickened, whereby when thrust in direction of the thickened portion of the reinforce occurs and tends to cause the reinforce to yield, the hook-ends engaging in the brass prevent yielding and breaking 95 of the brass.

In testimony whereof I affix my signature.

HAROLD G. MARTIN.
